(57) **CLAIM**

I claim the ornamental design for a wearable mobile device, as shown and described.

DESCRIPTION

FIG. 1 is a first-side perspective view of a wearable mobile device in accordance with the new design.

FIG. 2 is a second-side perspective view of a wearable mobile device of the wearable mobile device of FIG. 1.

FIG. 3 is a top view of the wearable mobile device of FIG. 1.

FIG. 4 is a bottom view of the wearable mobile device of FIG. 1.

FIG. 5 is a first side view of the wearable mobile device of FIG. 1.

FIG. 6 is a second side view of the wearable mobile device of FIG. 1.

FIG. 7 is a first end view of the wearable mobile device of FIG. 1.

FIG. 8 is a second end view of the wearable mobile device of FIG. 1.

FIG. 9 is a first side view of the wearable mobile device of FIG. 1, depicting the wristband unsecured.

FIG. 10 is a second side view of the wearable mobile device of FIG. 1, depicting the wristband unsecured.

FIG. 11 is a first end view of the wearable mobile device of FIG. 1, depicting the wristband unsecured; and,

FIG. 12 is a second end view of the wearable mobile device of FIG. 1, depicting the wristband unsecured.

The dashed lines depict parts of the wearable mobile device that form no part of the claimed design.

1 Claim, 4 Drawing Sheets
